UNITED STATES PATENT OFFICE.

JAMES W. MARKHAM, OF EVANSVILLE, INDIANA, ASSIGNOR OF TWENTY-TWO AND ONE-HALF ONE-HUNDREDTHS TO CHARLES F. WERNER AND TWENTY-TWO AND ONE-HALF ONE-HUNDREDTHS TO WILLIAM P. WALSH, BOTH OF EVANSVILLE, INDIANA.

SWITCH-OPERATING MECHANISM.

1,145,330.

Specification of Letters Patent.

Patented July 6, 1915.

Application filed February 9, 1915. Serial No. 7,077.

To all whom it may concern:

Be it known that I, JAMES W. MARKHAM, a citizen of the United States, residing at Evansville, in the county of Vanderburgh 5 and State of Indiana, have invented a new and useful Switch-Operating Mechanism, of which the following is a specification.

The present invention appertains to switch operating mechanisms, and is particularly an improvement over the switch operating mechanism disclosed in my patent 10 No. 1,123,338 issued January 5, 1915.

It is the object of this invention, to provide a novel actuating mechanism for the 15 switch piece or tongue, whereby the mechanism is operable by a device carried by the street car, to enable the motorman to throw the switch piece or tongue of the switch without leaving or stopping the car.

20 It is also within the scope of the invention, to provide a switch operating mechanism, which will be improved generally in its construction and details, to enhance the utility and efficiency thereof.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

30 The invention is illustrated in its preferred embodiment in the accompanying drawing, wherein—

Figure 1 is a plan view of the mechanism applied to a switch, portions being broken away. Figs. 2, 3 and 4 are enlarged sectional views, taken on lines 2—2, 3—3 and 4—4, respectively, of Fig. 1.

In the drawing, the numeral 1 designates the main track from which the side track or 45 switch is branched, there being an oscillatory switch piece or tongue 3 coöperable with the adjacent rails of the main and side track or branch, as usual.

The present mechanism is provided for

operating the switch piece or tongue 3, and 50 embodies a longitudinal plate 4 disposed between the rails of the main track 1 in advance of the side track or branch 2, and the plate 4 is provided with upturned flanges 5 along its side edges, and the rear end of 55 the plate 4 and its flanges 5 are flared, as at 6. An upright rock shaft 7 is journaled through the plate 4, and a trip lever 8 is secured upon the upper end of the shaft 7 so as to oscillate between the flanges 5 of 60 the plate 4, to be engaged by the car carried device (not shown) in the same manner as disclosed in the above mentioned patent. A laterally projecting arm 9 is secured to the lower end of the shaft 7, and has pivoted 65 thereto, the forward end of a connecting rod 10, which preferably comprises a pair of sections having their adjacent ends connected adjustably by means of a turn buckle 11, in order that the connecting rod 10 may 70 be adjusted properly. It is preferable to house the connecting rod 10 in a housing or casing 12, to protect the same from the elements, and traffic.

The operative connection between the rear 75 end of the connecting rod 10, and the switch piece or tongue 3, is preferably housed within a casing or box 13 mounted adjacent the switch piece, and having a cut away portion or recess 13^a within which the switch piece 80 works, and also having a removable cover or lid 14 for enabling access to be had to the parts housed within the casing or box. A bearing 15 is secured upon the bottom of the casing 13 adjacent the front wall thereof, 85 and the rear end portion of the connecting rod 10 is slidable through the bearing 15, a cam rod 16 being pivoted, as at 17, to the rear end of the connecting rod 10, and having its free end portion slidable through a 90 bearing 18 secured upon the bottom of the casing 13 adjacent the rear wall thereof. The bearing 18 is provided with a removable cap, which in being detached, enables the cam rod 16 to be swung upwardly. The 95 cam rod 16 is provided between its ends with a diagonal or oblique portion 19 forming a cam, which is fitted within an upper diagonal

or oblique groove 20 provided in an upstanding rib 21 carried by a slide 22, which is movable within a channel or recess 23 provided in the bottom of the casing 13. Thus, when 5 the connecting rod 10 is reciprocated, due to the oscillation of the trip lever 8, the cam rod 16 will be oscillated, and the cam portion 19 working through the groove or slot 20 of the slide 22, will cause the slide to be 10 reciprocated at right angles to the connecting rod 10, and switch piece.

The switch piece or tongue 3 is yieldably connected with the slide 22, to be actuated thereby, and to this end, a strip or bar 24 15 has one end connected or pivoted by means of a bolt or other securing means 25, to the switch piece or tongue 3, and the strip or bar 24 overlaps and rests upon the rib 21, and the free end of the strip or bar 24 which is 20 disposed upon the slide 22 is provided with upstanding or upturned ear 26 through which a rod or bolt 27 is slidable, parallel with the strip or bar 24. That end of the rod or bolt 27 remote from the switch piece 25 is threaded or engaged adjustably through an upstanding ear or lug 28 carried by the corresponding end of the slide 22, and a coiled wire expansion spring 29 is disposed upon the rod or bolt 27 between the ears 26 and 28, while a coiled wire expansion spring 30 is disposed upon the rod or bolt 27 between the ear 26 and the head 31 upon that end of the rod or bolt 27 nearest the 30 switch piece. The springs 29 and 30 balance 35 each other, to normally hold the strip or bar 24 at a neutral position relative to the slide 22, and to enable the strip or bar 24 to move relative to the slide 22, when the switch piece 3 is swung in either direction, due to 40 the movement of a street car from the right hand side of Fig. 1, to the left hand side thereof.

In operation, supposing the parts to be arranged as depicted in Fig. 1, when a street car approaches the switch, traveling on the track 1 from the left hand side of Fig. 1, the trip lever 8 may be thrown or oscillated so as to assume a position opposite to the position illustrated in Fig. 1, and which will 45 cause the arm 9 to be swung so as to draw the connecting rod 10 forwardly relative to the track. The trip lever 8 is oscillated by a car carried device (not shown), of the nature disclosed in the above mentioned application. When the connecting rod 10 is 50 moved forwardly, the cam portion 19 of the follower rod 16 in moving through the diagonal or oblique groove 20 of the slide 22, will cause the slide 22 to move toward the 55 switch piece or tongue 3. As a result, the strip or bar 24 will be moved with the slide 22, to swing the switch piece or tongue 3 to position against the adjacent rail, for directing the car straight ahead upon the main

track 1, whereas if the switch piece or tongue 65 is moved to the position illustrated in Fig. 1, the street car will be directed onto the side track or branch 2. When the trip lever 8 is swung to the position seen in Fig. 1, the connecting rod 10 will be moved rearwardly, 70 which will cause the slide 22 to be moved away from the switch piece or tongue 3, to swing the switch piece to the position seen in Fig. 1.

It is to be noted that the springs 29 and 30 75 are disposed between the bar or strip 24 and the slide 22, whereby the strip or bar 24 is yieldably moved by the slide 22, and this permits the switch piece or tongue 3 to spring out of the way when a car passes 80 along the main track or passes from the side track or branch onto the main track, from the right hand side of Fig. 1 to the left hand side thereof.

It is preferable to provide the bottom of 85 the casing or box 13 with a drain pipe 35, whereby the water may be drained from the casing or housing. The sides of the trip lever 8 are preferably beveled, and the flanges 5 of the plate 4 are preferably inclined, as seen in Fig. 4, in order that rocks or other foreign objects which might fall onto the plate 4 between the trip lever 8 and one or both of the flanges 5, will be readily lifted or deflected off of the plate 4 through 90 the action of the trip lever 8, or the passage of the car carried device over the plate 4 between the trip lever 8 and one of the flanges 5. When the cap of the bearing or pillow block 18 is removed, the cam or follower rod 100 16 may be swung upwardly, when it is desired to separate the parts within the casing or box 13, for purpose of repair, cleaning or replacement.

Having thus described the invention, what 105 is claimed as new is:—

1. In a mechanism of the character described, a slide, means for actuating the same, a strip attachable to a switch piece and overlapping the slide, that end of the strip which overlaps the slide having an upstanding ear, the remote end of the slide having an upstanding ear, a rod slidable through the ear of the strip and having one end attached to the ear of the slide, the 110 other end of the rod having a head, and coiled wire expansion springs mounted upon the said rod between the said ear of the slide and the said head of the rod and ear of the slide.

2. In a mechanism of the character described, a rod, a slide adapted for operative connection with a switch piece and having an upper diagonal groove, and a follower rod pivoted to one end of the aforesaid rod 115 125 and having a diagonal cam portion engaging the said groove.

3. In a mechanism of the character de-

scribed, a slide having an upper diagonal groove, an actuating rod, a follower rod pivoted to one end of the said rod and having a diagonal cam portion between its ends 5 engaging the said groove, and a bearing for the free portion of the follower rod having a removable cap.

In testimony that I claim the foregoing as my own, I have hereto affixed my signature in the presence of two witnesses.

JAMES W. MARKHAM.
